UNITED STATES PATENT OFFICE

CHARLES F. BENEDICT, OF NEW YORK, N. Y., ASSIGNOR OF TWO-THIRDS TO K. C. SEELBACH COMPANY, OF NEW YORK, N. Y., A CORPORATION OF NEW YORK

PLIER HANDLES OF SHEET METAL

Application filed March 19, 1928. Serial No. 262,837.

This invention relates to handles for pliers constructed of sheet metal stampings, and its object is to provide a form of construction in which width and form is given to the handle elements by bending a portion of each, under and back; the bending in each case being from the top face of the implement, and the result being, that an unbroken surface area is presented on the top face of 5 the implement from the joint to the rear extremity thereof; while the handle portions which are turned under present a uniform appearance and extend only from the rear extremity to a point near to the plier joint. 10 Another object is a means for the stiffening and strengthening of the joint; which means is provided by a form of swedging adjacent to the rivet of the said joint.

These and other objects and features of 20 the invention will be fully described in the following specification and claims, and illustrated in the accompanying drawings, in which:

Fig. 1 shows a top face view of a plier in 25 which the handle form is illustrated; the jaws being indicated in dot and dash lines.

Fig. 2 shows a section on the line 2—2 of Figure 1.

Fig. 3 shows a section through the joint on 30 the line 3—3 of Figure 1.

Fig. 4 shows the bottom, or reverse side of the implement and illustrates the underlapped portions of the handles.

Fig. 5 shows a section on the line 5—5 of 35 Figure 4.

Fig. 6 shows a top edge view of the upper element only, as illustrated in Figure 4.

The forming of pliers and similar implements of sheet metal is an old art, but certain 40 novel improvements are presented in this invention which greatly increase the serviceability of the tool as well as add to its symmetry of appearance.

Plier handles have previously been constructed in which turned over portions have 45 been bent from the main body of the handle element; but it is believed that, in all prior cases the elements have been so assembled that the said overlapped portions were turned in opposite directions to each other so that

looking at the plier from the top side, one of the portions would be turned upward and the other downward with respect to the said handle elements. Such a form of construction is ununiform and unbalanced and does 55 not present the symmetry of form and appearance which is apparent in the handles herewith illustrated.

The strength and appearance of the tool herewith shown is also enhanced by the 60 swedging of the metal adjacent to the joint rivet.

Referring now to Figure 1 of the drawings; the handles shown comprise the elements 10 and 11 which are joined together 65 by means of the rivet 12, or by a screw if desired. The jaws of the plier are indicated by the dot and dash lines 13 and may be of such varied forms as required either for gripping or for cutting purposes. The swedged 70 portion 14; while shown in ring formation, may be of any suitable geometric design, the object being to force portions of the metal into forms of contour in variable planes in order to better resist the bending and twist- 75 ing strains set up at this point when in use.

Referring now, to Figure 3; it will be seen that an underlapped portion 17 is bent over from the main body of the element 10; while a similar portion 18 is bent over from the 80 element 11, the portion 18 being slightly bent inward as shown.

In the reversed view as illustrated in Figure 4; the underlapped portions 17 and 18 may be clearly seen; they extend from the 85 rear extremity of the plier to a point back of the joint, terminating in the wide flared portions as seen at 19 and 20.

Referring to Figure 6 of the drawings; it 90 will be seen that the top surface of the element 11 is in a straight horizontal line; while the under side is bent downward below the line of the joint and the swedged ring 14. This metal is formed over in this manner to give gripping surface on the handle and to 95 strengthen it by reason of the contoured formation. Now, if the metal in the opposite handle element 10 were turned over in an upward direction in the manner commonly used prior to this invention; then the turned 100

over portion, if laid opposite to the element shown in this view would extend upward above the line of the joint just as the element 11 extends below it. This old style of construction throws the plier badly out of alignment and this is usually compensated for, to some extent by bending the handles diagonally across each other in the mid section of the plier.

10 This invention seeks to overcome this objectionable feature to some extent by bending both flared portions of the handle so that the portions 17 and 18, as seen in Figure 3, are both on one side of the handle. This 15 brings the lines of applied force closer together and produces a more efficient, and a better appearing tool. The turned over portions of both handles terminate in the wide flaring members 19 and 20 as seen in Figure 4.

20 Referring now to the illustration seen in Figure 5; it will be seen that the flared portion 18 is slightly bent inward. This is done to bring it into alignment with the portion 25 17 and gives a more symmetrical appearance. Otherwise it has no utility.

25 The form of construction herewith shown and described is, by reason of the better alignment of the handles, a more efficient and 30 practical tool than is found in sheet metal pliers as now made, and it also possesses greater symmetry and beauty of outline because the free end portions 19 and 20 are both on one side, and the top surface of the 35 tool presents an unbroken and uniform surface appearance.

Having thus described my invention, what I claim as new and desire to secure by Letters Patent, is as follows:

40 1. Lap jointed plier handles of sheet metal comprising opposed elements pivotally secured together at their forward extremities, embossed ring formations concentric to the pivot member and having concave portions 45 of the said ring formations so positioned as to form an annular chamber about the said pivot member, the said handle elements extending backward from the joint and portions of the said handle elements bent over 50 and back under in oppositely disposed U formations with the base portions of the U shapes outward.

55 2. Lap jointed plier handles of sheet metal comprising opposed elements pivotally secured together at their forward extremities, embossed ring formations concentric to the pivot member and having the concave portions of the said ring formations so positioned as to form an annular chamber about the said pivot member, the said handle elements extending backward from the joint, and portions of the bodies of the said elements bent over and under the same, and the bent over portions terminating in diagonally cut flared portions at a point back of

the said joint, and one of the said flared portions bent inward to align with the opposed flared portion of the adjacent handle element.

Signed at New York city, in the county of New York and State of New York, this 15th day of March, A. D. 1928.

CHARLES F. BENEDICT.
